United States Patent Office

Des. 196,240

Patented Sept. 10, 1963

196,240

NIGHT TABLE

Ralph P. Betts, Elgin, Ill., assignor to Metralin Co., Inc.,
Elgin, Ill., a corporation of Delaware

Filed June 5, 1961, Ser. No. 65,458

Term of patent 14 years

(Cl. D33—6)

I claim:

The ornamental design for a night table, as shown and described.
